BOX FOLDING APPARATUS

Isadore H. Weber, Philadelphia, Pa.

Application February 6, 1931, Serial No. 513,884

4 Claims (Cl. 271—87)

This invention relates to apparatus employed in the manufacture of corrugated paper boxes and the like and more particularly to an apparatus for facilitating not only the folding and handling of the preliminarily cut and scored sheets of which the boxes are fabricated but also the delivery thereof directly to a machine for performing a subsequent operation upon the sheets or to a point conveniently located with respect to said machine.

Heretofore and prior to this invention it has been the usual practice following the operations of scoring and cutting the flat sheets of which the boxes are fabricated to load the same upon a truck by which they were delivered to an apparatus for folding over the opposite ends of the box sheet, the sheets to be so folded being manually lifted from the truck to an elevated point where they were fed through the rollers of the sheet-folding apparatus. The sheets thus fed through the rollers of the folding apparatus were permitted to drop upon an inclined conveyor for gravitation to the lower end thereof. An operator stationed at the lower end of this inclined conveyor received each of the folded sheets as they were discharged from the conveyor and stacked them one upon the other for delivery to a machine for performing a subsequent operation upon the sheets. This necessitated the employment of one or more operators at each end of the folding apparatus, the operators at the feeding end being required to lift each sheet to be folded for insertion through the rolls and the operator at the discharge or delivery end of the apparatus being required to lift each folded sheet from the conveyor in order to properly stack them upon a truck for delivery to the next station in the line of operations.

Inasmuch as the sheets to be folded are frequently of large size and quite heavy, considerable effort is required to lift each sheet to the feeding position. In addition to this, the time consumed in separately lifting each sheet into feeding position materially decreases the possible output of the apparatus. What is true at the feeding end of the apparatus is likewise true at the discharge end thereof because it has been necessary for the operator at this end to separately lift each sheet from the conveyor for transference to a truck. Furthermore, the speed with which the sheets are fed through the folding rolls is dependent upon the speed with which the folded sheets are removed from the discharge end thereof, and vice versa, in consequence of which a slow operator at one end of the apparatus

naturally had the effect of slowing up the speed of operation of a faster operator at the other end.

It is accordingly among the principal objects of the present invention to provide an apparatus which is capable of overcoming the aforementioned difficulties and by virtue of which the output of the sheet folding apparatus is materially increased.

A further object of the invention is to provide an apparatus for facilitating the feeding of sheets through a set of sheet folding rolls as well as for facilitating the handling thereof at the discharge end of the apparatus.

Still another object of the invention is to provide an apparatus which is operative in such manner as to permit a single operator to feed without interruption a greater quantity of sheets through a pair of folding rolls than was possible heretofore, this being accomplished by means of a lift bearing a stack of sheets to be folded, the lift being elevated at a speed which is so regulated as to successively present each sheet of the stack beginning with the uppermost one thereof for projection rectilinearly from off the top of the stack toward and through the folding rolls of the apparatus. In other words, the lift is elevated at a speed such that an operator stationed on an elevated platform immediately behind the lift is merely required to project the topmost sheet of the stack forwardly and in the plane thereof for insertion through the rolls.

Still another and important object of the present invention is the provision of a sheet folding apparatus including a mechanism which is operative to effect the stacking of a predetermined number of folded sheets upon an inclined conveyor, this mechanism being automatically operative to release the stack for delivery to the discharge end of the conveyor.

A further object of the invention is the provision of a sheet-folding apparatus including a mechanism which is automatically operative to insure proper stacking of the folded sheets, this mechanism being further automatically operative to deliver to an operator at the discharge end of the apparatus said properly stacked pile of folded sheets.

A still further object of the invention is the provision of a stop mechanism for accumulating a pile of folded sheets on the conveyor, this mechanism being operative to automatically release the accumulated sheets, when the pile reaches a predetermined height, for delivery to an operator stationed at the discharge end of the conveyor.

Other objects and advantages of the invention will be apparent more fully hereinafter.

The invention consists substantially in combination, construction, location and relative arrangement of parts, all as will be described hereinafter, as shown in the accompanying drawings and as finally pointed out in the appended claims. In the said accompanying drawings which illustrate a preferred form and arrangement of the invention:—

Figure 1 is a top plan view of the apparatus constructed in accordance with and embodying the principles of the present invention;

Figure 2 is an end elevational view looking toward the discharge end of the apparatus;

Figure 3 is a side elevational view of the apparatus shown in Figure 1; and

Figure 4 is an enlarged detail view of the stop mechanism.

Referring now more particularly to the drawings it will be seen that the apparatus as constructed in accordance with the principles of the present invention include a pair of laterally spaced vertically extending standards 10—10 of substantially channel-shaped cross section to provide a pair of opposed vertically extending guides or run-ways 11—11. The upper, lower and intermediate portions of these standards are suitably interconnected by horizontally extending cross members to afford a rigid structure. As appears most clearly in Figure 3 the lower end of this structure is founded within a depressed pit 12 extending below the surface of the floor 13. Inclined braces 14—14, the upper end of which are respectively suitably secured to the upper ends of the standards 10—10 and the lower ends of which rest upon and are secured to the floor 13, assist in maintaining the interconnected standards in the vertical position shown.

Suitably mounted above the top of the standards 10—10 are a pair of horizontally disposed rolls 15 and 16, these rolls being arranged with their axes of rotation disposed in a common vertical plane. It will be understood that the opposite ends of each of the rolls 15 and 16 are respectively journaled within suitable bearing boxes 17 and 18, these boxes being preferably mounted within the channel-shaped vertically extending members 19. The upper pair of bearing boxes 17 are preferably vertically adjustable whereby the upper roll 16 may be elevated or lowered to vary the clearance between it and the lower roll 15. Extending laterally from the upper end of one of the standards 10—10 is a horizontally disposed shelf 20 upon which is mounted an electrically operated motor 21 the shaft 22 of which is suitably geared to the lower roll for imparting rotation thereto, it being understood that the sheets to be folded are fed through the rolls 15 and 16. Respectively secured to and extending forwardly from the supporting members 19 for the bearing boxes are a pair of brackets 24 between the free ends of which is supported a horizontally extending rod 25. Supported upon this rod 25 for free rotation thereon is a relatively short roll 26, this roll 26 being arranged centrally between the standards 10 and in advance of the upper roll 16.

Suitably mounted within the bottom pit 12 is a bracket 27 affording a shelf or base for a second electrically operated motor 28. Respectively journaled adjacent the upper and lower end of each of the vertically extending standards 10—10 are a pair of sprocket wheels 31 and 32 around which extends an endless sprocket chain 33. Journalled between the vertically extending

standards 10—10 immediately above the axis of rotation of the lower set of sprocket wheels 32 is a shaft 34 which is connected by means of a belt drive 35 or the like to the shaft of the motor 28. This shaft 34 which is thus driven by the motor 28 is also provided adjacent either end thereof with a pair of sprocket wheels 36 for respectively driving the sprocket chains 33.

Extending between the standards 10—10 is a carriage having upon each of the opposite sides thereof a pair of vertically spaced rollers 35' and 36', each pair of these rollers 35' and 36' being adapted to travel vertically in the channels or run-ways respectively formed in the standards 10—10. The carriage is secured to the laterally spaced sprocket chains 33 preferably by means of the bolts 37 and is provided with a rearwardly projecting table or support 38. It will be understood that the rollers 35' and 36' arranged at each side of the vertically movable carriage serve to maintain the upper surface of the rearwardly extending support 38 in a substantially horizontal plane. The pit 12 is of a size sufficient to receive the vertically disposed portion 39 of the carriage when the latter is in its lowermost position with the horizontally extending portion 38 thereof resting upon the floor a surface 13.

Suitably secured to one of the standards 10—10 is an electrical control box 40 within which is housed the switching gear (not shown) for starting, stopping and reversing the direction of rotation of the motor 28. Operatively mounted upon the vertically extending frame of the apparatus adjacent the upper end thereof is a top stop switch 41, while similarly associated with the frame adjacent the bottom end thereof is a bottom stop switch 42. These top and bottom stop switches 41 and 42 are respectively electrically connected to the switching gear in the control box 40 by way of the conductors 43' and 44', it being further noted that these stop switches project into the path of movement of the vertically movable work supporting carriage. In other words, the top stop switch 41 is so located that when the upper surface of the table 38 reaches a predetermined elevation the switch is engaged and actuated to open the motor circuit and so interrupt further upward movement of the carriage. Similarly, the bottom stop switch 42 is so located that when the work supporting carriage reaches a predetermined point in its downward travel the bottom end of the depending portion 39 of the carriage engages and actuates the switch 42 to so automatically interrupt the further downward movement of the carriage.

Arranged immediately to the rear of the path of movement of the work supporting carriage is an elevated platform 43 upon which is stationed an operator for feeding the sheets to be folded through the feed rolls 15 and 16 of the apparatus. Provided in the upper surface of this platform is a foot actuated switch mechanism 44 which is electrically connected by means of the conductor 45 with the switching gear housed within the control box 40. This foot controlled switch mechanism 44 includes a spring-pressed plunger 46 which is normally maintained in open circuit position, the motor circuit being closed only when the operator depresses this plunger 46 with his foot.

It will be understood that the horizontally extending portion 38 of the vertically movable carriage constitutes a table or support for a stack of sheets 5 which are to be individually fed through

the folding rolls 15 and 16. These sheets are delivered to the apparatus in any suitable manner but preferably by means of a truck (not shown) which is wheeled from the cutting and scoring machines to the present apparatus. The preliminarily cut and scored sheets are placed flatwise upon a platform 47 or the like which in turn is placed upon the delivery truck, the sheets being stacked upon this platform to any convenient height desired.

The vertically movable carriage of the apparatus is lowered to its lowermost position and the platform 47 with its stack of sheets *s* is transferred from the truck to the horizontally extending portion 38 of the carriage. The operator then mounts the elevated platform 43 and actuates the switch 44 to start the motor 28 and so cause the carriage to move upwardly. When the topmost sheet of the stack reaches an elevation such that it lies substantially in the horizontal plane of the bight of the feed rolls 15 and 16, the operator moves the said topmost sheet forwardly and into engagement with said rolls, it being understood that before so feeding the sheet to the rolls the opposite ends thereof are folded inwardly and against the flat intermediate body of the box sheet. The speed at which the carriage is elevated is so regulated with respect to the speed with which the operator works that the top of the stack of sheets *s* is substantially in the same plane at all times as each folded sheet is fed through the feed rolls. If desired, the operator may impart an intermittent elevating movement to the carriage by intermittently actuating the switch mechanism 44 so as to successively present the topmost sheet of the stack in position to be rectilinearly shifted through and between the folding rolls 15 and 16.

Extending in advance of the vertically disposed standards 10-10 is an inclined conveyor 48 the upper end of which is suitably secured to the upper end of the carriage guide frame. This conveyor 48 preferably comprises an open rectangular frame the longitudinally extending side members 49-49 of which are in the form of channel members between which are journaled a series of rollers 50. These rollers 50 provide a top roller surface for receiving the folded sheets which are fed through the rolls 15 and 16 for gravitation toward the lower end thereof. In the operation of this apparatus it is desirable from the standpoint of efficiency to effect the delivery to the lower end of the conveyor of a stack of folded sheets rather than permit the delivery of one folded sheet at a time. In order to effect this desirable result the conveyor is provided with a stop mechanism designated generally by the reference numeral 51 and which mechanism will now be described.

As appears quite clearly in the drawings, this stop mechanism is supported in vertically spaced relation above the inclined conveyor 48 by means of a supporting framework 52. Included in this framework 52 are a pair of longitudinally extending members 53-53, these latter members being respectively spaced above and in parallelism with the inclined side members 49-49 of the conveyor frame. Pivottally secured, as at 54, to each of the members 53-53 is an arm 55, the upper end 56 of which projects above the plane of the members 53-53 while the lower end 57 thereof terminates immediately above the roller surface of the conveyor.

Also secured to each of the members 53-53 and extending perpendicularly with respect

thereto is a fixed arm 58 to the upper end of which is pivotally secured, as at 59, an arm 60. Each of these arms 60 is provided in its free end with a downwardly presenting notch 61 within which is adapted to be received the upper extremity 56 of the associated pivotally mounted stop member 56. It will be observed that when the arm or detent 60 thus engages the upper end of the stop arm 56 the latter will be held against movement and in a position substantially normal to the conveyor surface.

Suitably carried by the fixed arm 58 is a bracket element 62 within which is threadedly secured a stud or pin 63 the upper end of which constitutes a bottom abutment or stop for the detent 60. Spring means 64 tend constantly to draw this detent downwardly into engagement with the upper end of the stud or pin 63. It will be understood that by vertically adjusting the position of this stud 63 the lowermost position of the detent may be varied as desired.

Pivoted to the lower end of the fixed arm 58 is a rearwardly extending arm 65 the free end of which is provided with a freely rotatable wheel 66. This wheel arm 65 is provided with an upwardly projecting arm 67 adapted to engage the detent 60 for effecting the latter's disengagement from the stop member 56. The upper end of the arm 67 may be provided with an adjustable extension 68 for varying the effective length of the arm 67 and so vary the degree of movement necessary for the wheel arm 65 to lift the detent 60 free from the stop member 56. As a guide for the wheel arm 65 and to insure its movement in a vertical plane a bifurcated member 69 is secured to the rail 53, the forked portion of said member 69 being so arranged as to straddle the wheel arm 65 during the movement of the latter. If desired and in order to insure unison of movement between the wheels 66 the latter may be commonly journalled upon a shaft which extends between and interconnects the free ends of the wheel arms 67-67.

In the operation of the apparatus the operator first places upon the vertically movable platform 38 a stack of sheets *s* to be folded. The operator then mounts the elevated platform 43 and actuates the switch mechanism 44 to cause the platform to move upwardly. When the topmost sheet reaches the horizontal plane of the bight of the feed rolls 15 and 16 it is moved forwardly through and between these rolls, the opposite ends of the sheet being first folded over. As each sheet reaches the aforesaid plane it is folded and shifted forwardly through the feed rolls. As each folded sheet emerges from between the feed rolls it drops upon the inclined conveyor 48 and moves downwardly along this conveyor until the rear end thereof engages the arm 55. It will be understood that the sheets from the stack *s* are folded and fed consecutively through the feed rolls so that eventually they are received in the form of a stack upon the conveyor 48.

As this stack of folded sheets on the conveyor increases in height the topmost sheet thereof engages the rotatable wheels 66. It will be understood that as the folded sheets are passed through the feed rolls 15 and 16 they are projected downwardly by the free roll 26 and below the wheels 66. These wheels 66 are relatively so arranged that they respectively engage the opposite flaps of the folded sheet, the wheels being further of sufficient weight to maintain these flaps in depressed condition. It will be understood that as the stack of sheets on the conveyor 48 increases

in height the wheels 66 are raised to a point sufficient to effect engagement between the upper end of the fixed arm 67 and the pivotally mounted 5 detent 60. As long as this detent 60 is in engagement with the stop arm 55, as is most clearly shown in Figure 1, the stack of folded sheets on the conveyor 49 is maintained in the position shown. When, however, the stack of sheets on 10 the conveyor reaches a height sufficient to raise the wheels 66 to an extent sufficient to effect disengagement between the detent 60 and the stop arm 55, the latter is free to move about its pivotal point 54. The stop arms 55 are then no longer 15 operable to maintain the stack of folded sheets in position in consequence of which the stack, by reason of its own weight, gravitates toward the lower end of the inclined conveyor 48.

It will be understood of course that the stop mechanism is adjustable to accommodate sheets 20 of different sizes and to provide for a stack of greater or less height. It will thus be seen that when the stack of sheets on the conveyor 48 reaches a predetermined height or consists of a 25 predetermined number of folded sheets, the detent 60 is actuated to release the normally stationary stop arm 55 thereby permitting the stack to gravitate towards the lower end of the conveyor, where it is received by an operator stationed at that point.

30 It will be understood of course that the invention or inventions herein disclosed are susceptible of various changes and modifications without departing from the real spirit or principles thereof and it is accordingly intended to claim the same broadly, as well as specifically, as indicated by the 35 appended claims.

What is claimed as new and useful is:—

1. In an apparatus of the character described, 40 in combination, an inclined conveyor upon which sheets are permitted to gravitate toward the lower end thereof, means for feeding sheets to said conveyor, means for precluding the gravitation of said sheets whereby the same are piled into the form of a stack, and means operable automatically 45 to release the stack for gravitation toward the lower end of the conveyor when the stack reaches a predetermined height.

2. In an apparatus of the character described, 50 in combination, an inclined conveyor for delivering sheets toward a given point, means for feeding sheets to said conveyor, stop means opera-

tively associated with the conveyor for precluding the movement of said sheets beyond a predetermined point on said conveyor whereby the sheets are caused to pile in the form of a stack, and means actuated by a stack of sheets of predetermined height or number to render said 5 means ineffective to retain the stack against movement.

3. In an apparatus of the character described, 10 in combination, an elevated set of rollers, a vertically movable carriage for supporting a stack of sheets to be fed through said rollers, means for controlling the movement of said carriage whereby to successively present said sheets in position to be fed rectilinearly through said rollers, an inclined conveyor for delivering the sheets discharged from said rollers to a given point, means operatively associated with said conveyor for precluding the movement of said discharged sheets beyond a predetermined point on the conveyor 15 whereby the sheets are caused to pile in the form of a stack, and means operable automatically to release the stack for movement along the conveyor when said stack reaches a predetermined height.

4. In an apparatus of the character described, 20 in combination, a rigid framework including a pair of laterally spaced standards, a pair of horizontally arranged rolls supported above said framework, a movable carriage movable vertically 25 between said standards and including a rearwardly extending table for supporting a stack of sheets to be fed through said rolls, an elevated platform arranged to the rear of the path of movement of said table and upon which an operator 30 may be stationed, means for controlling the upward movement of said carriage whereby to successively present the topmost sheet of the stack in position to be fed rectilinearly through the rolls, an inclined conveyor operatively associated with said feeding rolls for receiving a plurality of said sheets in stacked relation, means 35 operative to temporarily retain in immovable position upon said conveyor a predeterminedly fixed number of said sheets in said stacked relation, and means for releasing said stack of sheets whereby to permit said conveyor to convey the 40 stack of sheets by gravity to a point removed from the feeding rolls.

50 ISADORE H. WEBER.
